UNITED STATES PATENT OFFICE.

FRED J. EWERS, OF SACRAMENTO, CALIFORNIA.

WIRE CRIMPER.

Application filed January 29, 1925. Serial No. 5,495.

This invention relates to new and useful improvements in wire crimpers.

The primary object of the invention is to provide a machine adapted for crimping wire mesh, or the like, which is fed through the machine in web form.

A further object of the invention is to provide a machine adapted for forming different sized and shaped crimps and for arranging 10 the various crimps in longitudinal alinement or in staggered or overlapping relation in respect to the length of the web of material being handled.

Other objects and advantages of the invention will be apparent during the course of 15 the following description.

In the accompanying drawings forming a part of this specification and in which like numerals are employed to designate like 20 parts throughout the same,

Figure 1 is a side elevational view of the wire crimping machine embodying this invention,

Figure 2 is a top plan view of the machine 25 shown in Fig. 1,

Figure 3 is a longitudinal sectional view taken upon lines III—III of Fig. 2,

Figure 4 is a transverse sectional view taken upon lines IV—IV of Fig. 1,

30 Figure 5 is an end elevational view, partly in section, of the female crimping or die roll forming part of the machine illustrated in Figs. 1 to 4 inclusive,

Figure 6 is a fragmentary elevational view 35 of the roll shown in Fig. 5,

Figure 7 is an end elevational view, partly broken away, of the male crimping or die roll operatively associated with the roll shown in Figs. 5 and 6,

40 Figure 8 is a similar view to Fig. 6 of the roll shown in Fig. 7,

Figure 9 is a fragmentary transverse sectional view of a wire mesh formed with a crimp by the machine depicted in the preceding figures,

Figure 10 is a longitudinal sectional view of the wire mesh taken upon line X—X of Fig. 9,

Figure 11 is a similar view to Fig. 10, but 50 shows a different form of crimp,

Figure 12 illustrates in fragmentary perspective a detachable crimping or die element adapted to be associated with the roll shown

in Figs. 5 and 6 and adapted for forming the type of crimps illustrated in Fig. 11,

Figure 13 illustrates in fragmentary perspective a crimping or die element adapted to be associated with the roll illustrated in Figs. 5 and 6, and

Figure 14 illustrates in perspective the 60 type of removable crimping or die elements shown associated with the roll illustrated in Figs. 7 and 8.

In the drawings, wherein for the purpose of illustration is shown a preferred embodiment of this invention, the numeral 5 designates the base plate of the frame portion of the machine embodying this invention. This base plate 5 has integrally formed with its longitudinal edge portions the perpendicularly extending skeleton sides which include the end bars 6 and 7 and the central bar 8, the said bars 6, 7 and 8 being joined at their upper ends by the top bar 9. Suitably connected to the top faces of these top bars 9 of both of the sides is a cross bar 10 which aids in bracing and maintaining in alinement the said skeleton sides.

Journalized in the central bars 8 are the parallel, transversely extending shafts 11 and 12 which are connected to rotate at the same speed by the spur gears 13 and 14. The shaft 12 is provided with a fixed pulley 15 and a loose pulley 16 adapted to be associated with a drive belt extending from a suitable source of power, not shown.

Mounted upon the shaft 12 and suitably keyed, splined, or fastened thereto is what will be termed the female crimping or die roll 17. This roll 17 has formed in its periphery four equi-spaced, longitudinally extending grooves 18 which are of square or rectangular formation in cross-section and extend the full length of the roll. Removably fitted in these grooves 18 are the metallic female die elements 19 depicted in detail in Fig. 12. This roller is further provided with four equi-spaced, longitudinally extending grooves 20 which are V-shaped in cross-section and have removably fitted therein the metallic crimping or die elements 21 which are depicted in detail in Fig. 13. These grooves and elements 20 and 21 also extend the full length of the roll 17.

Similarly mounted upon the shaft 12 is 105 the male crimping or die roll 22. This roll

22 is adapted for having removably mounted upon its periphery the male die elements 23 which are V-shaped in cross-section and register with the V-shaped female die elements 21 when the rolls 17 and 22 are rotated. This roll 22 is illustrated in Figs. 7 and 8 as being provided with short sections of male crimping or die elements 23 which are arranged in staggered relation in respect to each other for forming crimps in a web of material with the crimps arranged in staggered relation in respect to each other and to the length of the web. It is to be understood that the male crimping or die elements 23 may be of any suitable length for forming crimps the full width of the web of material or any fragmentary portion of said width and that the said crimps may be formed in longitudinal alinement or in staggered or overlapping relation in respect to each other. In Fig. 7, the roll 22 is illustrated as having formed therein additional threaded openings 24 which are to be employed for permitting male crimping or die elements of square or rectangular cross-sectional formation to be secured to the periphery of the roll 22 and to register with the female crimping or die elements 19 carried by the female roll 17. These male crimping or die elements may be used in connection with the V-shaped crimping dies or independently thereof, when used independently of the V-shaped crimping dies, the die elements 23 will be removed from the roll 20. The male crimping or die elements adapted to cooperate with the female die elements 19 are not shown in detail, but it will be understood by comparing Figs. 13 and 14 that the male die elements, of square or rectangular formation will form the same relation with the female die elements 19 shown in Fig. 12 as does the male die element 23 with the female die element 21, shown in Figs. 14 and 13 respectively. In Figs. 1 and 2, the end bars 6 of the opposite skeleton sides are each illustrated as having integrally formed therewith a pair of ears 25 having a transverse pin 26 secured thereto which pivotally supports a clamping element 27 adapted to be selectively connected at its free end to the said end bar 6 by the bolt 28. This clamping element 27 is suitably channeled at 29 for receiving the ends of the bearing block or bushing 30. Journaled in these bearing blocks 30 and clamping elements 27 is a transverse shaft 31 having disks 32 mounted thereon. This shaft 31 is intended to receive the web of material after it has been passed between the crimping or die rolls 17 and 22 and provided with the desired crimps, the disks 32 being employed for engaging the edges of the web of material for causing the same to be properly wound upon the shaft 31.

65 The end bars 7 of the opposite skeleton

sides are also provided with ears 25 which carry the pin 26 having the clamping elements 27 pivotally mounted thereon and adapted to be selectively connected at their free ends to the bars 7 by the screws 28. 70 These clamping members 27 are also channeled at 29 for receiving the bearing blocks or bushings 30. Journaled between the bearing blocks or bushings 30 and the clamping elements 27 is a shaft 33 which is provided with end disks 34. This shaft 33 with its end disks 34 are intended to support and guide the web of material prior to its being passed through the machine for being crimped. 80

In Figs. 2 and 4 the shaft 12 is illustrated as having mounted on one end thereof the sprocket wheels 35 which have riding thereupon the sprocket chains 36 that extend to and ride upon sprocket wheels 37 carried by 85 the ends of the shafts 31 and 33. It will now be seen that when the shaft 12 is driven for rotating the rolls 17 and 22, the shafts 31 and 33 will also be rotated for feeding the web of material M from the shaft 33 through 90 the machine to be wound upon the shaft 31.

Depending from the top bars 9 and adjustable transversely in respect thereto are the material guiding arms 38 which operate for keeping the web of material aligned with 95 the crimping or die rolls 17 and 22.

The material M shown in Figs. 1, 2, and 3, while being passed through the crimping machine, is illustrated as having formed therein the crimps C. These crimps are of 100 V-shape as shown in Figs. 9 and 10 and are formed by the V-shaped male and female crimping or die elements 23 and 21. In Fig. 11, the material M is illustrated as having crimps C' formed therein which are of 105 square or rectangular formation in cross-section. These crimps C' are, of course, formed by the square or rectangular male and female die elements described above.

It is now believed that the construction, 110 manner of assembly, and the operation of this crimping machine will be understood from the above detail description and that no further explanation is deemed necessary.

It is to be understood that the forms of 115 this invention herewith shown and described are to be taken as preferred examples of the same, and that various changes in the shape, size, and arrangement of parts may be resorted to without departing from the spirit 120 of the invention or the scope of the subjoined claim.

Having thus described the invention, I claim:—

In a wire crimping machine, a machine 125 frame, journal bearings at opposite ends of the frame, winding and spending rollers journaled in the bearings, a shaft carrying each roller and projecting laterally of the frame at one side, a sprocket wheel fixed to 130

the projecting ends of the shafts, a pair of crimping rollers journaled in the frame between the winding and spending rollers, journaled shafts supporting the crimping rollers with one of the shafts projecting from one side of the frame and the other shaft projecting from both sides thereof, sprocket wheels on the projecting ends of the last named shafts with two of the sprocket

wheels forming connection between the shafts supporting the crimping rollers, a source of power associated with one shaft of the crimping rollers and sprocket chains connecting the remaining sprocket wheels on the several shafts.

15

In testimony whereof I affix my signature.

FRED J. EWERS.
